UNITED STATES PATENT OFFICE.

EDWARD L. DAWES, OF NEW BRIGHTON, PENNSYLVANIA.

DESIGN FOR A BATH-TUB.

SPECIFICATION forming part of Design No. 22,809, dated September 26, 1893.

Application filed July 8, 1893. Serial No. 479,956. Term of patent 7 years.

To all whom it may concern:

Be it known that I, EDWARD L. DAWES, of New Brighton, in the county of Beaver and State of Pennsylvania, have invented a new and original Design for a Bath-Tub, of which the following is a full, clear, and exact description, reference being had to the accompanying drawing, forming part of this specification, which shows in perspective view, partly in section, a bath tub embodying the design.

My design consists in a bath-tub shaped substantially as hereinafter described, viz., a bath-tub having a rolled rim extending around the greater portion of the tub, part of the rim, however, being substantially flat, and projecting horizontally beyond the rolled portion of the rim.

In the drawing, 2 represents the body of the tub.

3 is the rolled rim, which is convex on its surface and concave on its under side and extends around the greater portion of the tub, and 4 is a substantially flat portion of the rim, which has a greater horizontal projection than the rolled portion.

I claim—

The design for a bath tub substantially as herein shown and described.

In testimony whereof I have hereunto set my hand.

EDWARD L. DAWES.

Witnesses:

THOMAS W. BAKEWELL,
H. M. CORWIN.
